CLAIM

I claim the ornamental design for a sink mounted paper towel roll holder, as shown and described.

DESCRIPTION

FIG. 1 is a front view of the sink mounted paper towel roll holder showing my new design.

FIG. 2 is a rear elevation view thereof.

FIG. 3 is a left side elevation view thereof.

FIG. 4 is a right side elevation view thereof.

FIG. 5 is a top plan view thereof; and,

FIG. 6 is a bottom plan view thereof.
